UNITED STATES PATENT OFFICE.

LOUIS S. DLUGOSCH, OF STORM LAKE, IOWA.

HOT-WATER-CIRCULATING SYSTEM.

Application filed February 29, 1924. Serial No. 696,026.

To all whom it may concern:

Be it known that I, LOUIS S. DLUGOSCH, a citizen of the United States, residing at Storm Lake, in the county of Buena Vista and State of Iowa, have invented certain new and useful Improvements in Hot-Water-Circulating Systems, of which the following is a specification.

This invention relates to new and useful improvements in hot water circulating systems and has for its principal object to provide a means in connection therewith for preventing the drawing of cold water from the feed boiler when the faucet is opened.

Another important object of the present invention is to provide a hot water circulating system of the above mentioned character, which is of such a construction as to insure an instant supply of hot water at all times provided that the water in the boiler has been heated.

A further object of the present invention is to provide a hot water circulating system of the above mentioned character, wherein automatic means is provided for preventing the downward flow of the cold water when the faucet in the pipe line is opened to draw warm water.

A still further object of the present invention is to provide a hot water circulating system of the above mentioned character which is simple in construction, inexpensive, strong and durable, and further well adapted for the purposes for which it is designed.

Other objects and advantages of this invention will become apparent during the course of the following description.

In the accompanying drawings forming a part of this specification and in which like numerals designate like parts throughout the same:

Figure 1 is a side elevation of my hot water circulating system wherein a vertical valve is associated therewith.

Figure 2 is a vertical sectional view of the valve casing showing the valve in position therein.

Figure 3 is a view similar to Figure 1 showing a horizontally arranged valve in connection with the circulating system.

Figure 4 is a fragmentary detail view showing a modification of the horizontal valve casing.

Figure 5 is a longitudinal sectional view

of the valve casing shown in Figure 4 with the valve in position therein.

In the drawings, wherein for the purpose of illustration is shown the preferred embodiment of my invention, the numeral 1 designates a hot water tank or feed boiler which is of the well known construction the same being provided with the usual water supply pipe 2 which extends through the top 3 of the tank and downwardly into the tank in the manner as shown in Figure 1 of the drawings. Extending upwardly from the top 3 of the tank 1 is a circulating conduit including a vertical pipe 4 and the upper end thereof is connected by any suitable coupling to the horizontally extending section of pipe 5. The latter pipe 5 is also connected by a suitable coupling to the vertically extending pipe 6 and this pipe 6 extends for a distance below the bottom 7 of the water tank 1 as is clearly illustrated in the drawings.

The lower end of the vertically extending pipe 6 is connected to the horizontal section 8 and by means of a suitable coupling the last mentioned pipe is connected to the vertically extending pipe 9 which communicates with the bottom 7 of the water tank 1. The pipe sections 4, 5, 6, 8 and 9 when connected together, form what may be broadly defined as a circulating conduit. In this manner, it will be readily seen that a continuous circulation will be provided from the top of the tank 1 to the bottom thereof for the purposes to be hereinafter more fully described. Arranged in the vertical pipe 6 at any desired position, is a suitable coupling 10 to which a house supply pipe 11 is connected. Also located in the circulating pipe, preferably in the horizontal section 8, is a faucet 12 of a well known construction.

Arranged in the vertical pipe 9 which comprises an upper section and a lower section, is the valve casing 13. The valve casing 13 is substantially tubular in cross section as is clearly shown in Figure 3 of the drawings, and has its upper and lower ends respectively, connected to the upper section and lower section of the vertical pipe 9. To this end, I provide the upper end of the tubular valve casing 13 with an internally threaded nut portion 14, the opposite or lower end of the same being internally threaded to receive the threaded portion of 110

the fitting 15. A suitable gasket, such as is shown at 16 in the drawings, is disposed between the lower edge of the tubular casing 13 and the shoulder 17 of the fitting 15. 5 The opposite end of the fitting 15 is internally threaded for connection to the lower section of the vertical pipe 9. The fitting 15 with a central opening 18 terminates at its upper end in a conical valve seat 19. 10 Adapted for reciprocatory movement within the casing 13, is the valve 20. This valve 20 is preferably formed of copper and has its ends rounded, as is clearly shown in Figure 2 of the drawings. The lower end of 15 the valve 20 is adapted to seat on the valve seat 19 provided at the upper end of the fitting 15 when in one position, and to limit the upward movement of the valve 20 within the casing 13 I provide a cross piece 21 adjacent the upper end of the casing 13. 20

Ordinarily, with the hot water circulating systems now in use, when it is desired to draw off hot water from the tank, a person has to wait a few minutes in order to enable 25 the cold water standing in the piping to pass through the outlet pipe before the warm water reaches the spigot or faucet. In the arrangement as shown in Figure 1 of the drawings, the necessity of having to 30 draw off the cold water first is eliminated since warm water will at all times be within the circulating pipe so that upon opening the faucet, a current of hot water may be immediately obtained. Normally, the valve 35 20 is held out of engagement with the valve seat 19 due to equal pressure being placed on both sides of the valve so that a continuous circulation of water from the tank 1 to the top thereof and through the pipe 6 and 40 finally through the bottom of the tank will be provided. In this manner, warm water at all times is circulated through the pipe 6 and through the boiler 1, it being understood of course that the tank is initially 45 heated in any well known manner. When the faucet 12 is opened, the back pressure on the valve 20 will cause the same to seat against the valve seat 19 preventing a downward flow of water through the pipe 9 thus 50 preventing any cold water from entering the pipe and causing the warm water to rise through the pipes 4, 5 and 6 and to be drawn off finally by the faucet 12.

55 In Figure 3 of the drawings, a similar arrangement is shown wherein the circulating pipe 22 is connected to the top and bottom of a water tank 23. A valve casing 24 is associated with the circulating system and 60 is arranged horizontally and disposed in the horizontally extending section of pipe 25, in the manner clearly shown. The circulating pipe 22 is provided with the usual drain faucet 26 in the vertical section thereof. The valve casing 24 has its inner end 65 internally threaded to receive the fitting 27

which is substantially of the same construction as the fitting 18 heretofore described and provided with the valve seat 28 and the internally threaded portion 29 for connection with the horizontal pipe 25. The 70 fitting 27 is provided with the central opening 30 similar to the opening 18 provided in the fitting 15. The opposite end of the valve casing 24 is provided with an extension 31 which is also internally threaded for connection to the vertical section of pipe 32 extending from the bottom of the water tank 23. The extension 31 is preferably arranged adjacent the outer end of the valve casing 24 and adapted to be threaded into the outer 80 end of the valve casing 24 is the closure plug 33.

The valve casing 24 is also substantially tubular in cross section as shown in the drawings, and formed on the bottom thereof 85 and arranged in spaced relation are the guides 34. These guides are arranged preferably adjacent the inner end of the valve casing and are adapted to cooperate with the valve seat 28 of the fitting 27 in permitting the valve 35 which is in the form of a ball to travel in the casing in such a manner as to permit the valve to readily seat against the valve seat 28 when in one position and to engage the stop 36 when in the other position. 90

In Figure 4 of the drawings, a still further modification of the valve is shown wherein the horizontally disposed valve casing 37 has its respective ends connecting the horizontal sections of pipe 38, the latter being connected to the vertically extending section of pipe 39 which communicates with the bottom of the water tank 40. The closure plug 41 associated with the valve casing 37 is preferably threaded into the extension 42 formed on the upper portion of the valve casing 37 adjacent the ends thereof. The valve structure associated with the valve casing 37 is identical with the valve structure shown in Figures 6 and 7 and it is not thought necessary to describe the same. 100

The operation of the valve 35 within the valve casing 24 is substantially the same as the valve action in the case of the vertically arranged device shown in Figures 1 and 2 of the drawings, and heretofore more fully described. 115

It will thus be seen from the foregoing description, that a hot water circulating system has been provided wherein automatic means is associated therewith for preventing the downward flow of cold water through the circulating pipe when the faucet is opened to draw off warm water and consequently a continuous circulation of warm water will be caused to pass through the water tank and through the circulating pipe so that a person does not have to wait in order to obtain warm water. The simplicity 120 125 130

of my device enables the same to be readily assembled and does not require any attention on the part of a person desiring hot water nor is any mechanical means necessary in order to prevent the cold water which is always in the bottom of a water tank from being discharged through the faucet.

While I have shown the preferred embodiment of my invention, it is to be understood that various changes in the size, shape and arrangement of parts may be resorted to without departing from the spirit of the invention and the scope of the subjoined claim.

Having thus described my invention, what I claim is:

A water circulating system comprising a tank, a water supply pipe leading into the tank and terminating adjacent the bottom

thereof, a water circulating conduit connected at its upper end to the top of said tank 20 and connected at its lower end to the bottom of the tank, a portion of said conduit being disposed on a level below the bottom of the tank, a house supply pipe communicating with said circulating conduit, a check valve 25 in said circulating pipe adapted to prevent the flow of water from the bottom of the tank through said conduit, and a water discharge spigot for the tank also in the circulating conduit, said spigot being disposed below the bottom of the tank, and said check valve being disposed between the spigot and the bottom of the tank.

In testimony whereof I affix my signature.

LOUIS S. DLUGOSCH.
